(57) **CLAIM**

The ornamental design for a freight container, as shown and described.

DESCRIPTION

1. Freight container

1.1 is a perspective view of a freight container showing our new design;

1.2 is a front elevation view thereof;

1.3 is a rear elevation view thereof;

1.4 is a left side elevation view thereof;

1.5 is a right side elevation view thereof;

1.6 is a top plan view thereof; and

1.7 is a bottom plan view thereof.

The broken lines in the reproductions illustrate portions of the freight container that form no part of the claimed design.
